UNITED STATES PATENT OFFICE.

THOMAS F. RUSSELL, OF SPOKANE, WASHINGTON.

ADDRESSING AND INSERTING MACHINE.

Specification of Letters Patent.

Patented July 14, 1914.

1,103,846.

Application filed August 11, 1913. Serial No. 784,283.

To all whom it may concern:

Be it known that I, THOMAS F. RUSSELL, a citizen of the United States, residing at Spokane, in the county of Spokane and State of Washington, have invented certain new and useful Improvements in Addressing and Inserting Machines; and I do hereby declare the following to be a full, clear, and exact description of the invention, such as will enable others skilled in the art to which it appertains to make and use the same.

This invention relates to new and useful improvements in addressing machines and as its principal object contemplates the provision of a machine of this character in which there is provided an endless chain designed to receive the name plate from a suitable magazine, conduct the name plate to its proper position, and relation for printing, and to convey it from its printing position to a receiving magazine.

An object of equal importance with the foregoing is to construct the machine of this invention in such a manner that the actuation and operation of the various elements will be continuous and need not be regularly interrupted or be intermittent in its character, for it has been found in practice that machines of this type become mechanically faulty in less time by far than a machine in which the various elements operate continuously.

A further object is to provide novel means for mechanically depositing the name plates or address plates on the block carrier of the endless chain.

A yet further object resides in the construction of a receiving magazine which is adapted to automatically remove the name or address plates from the block carrier immediately after the name plates have passed through between the two platen drums and is equipped with means for automatically enlarging the volume of the plate receiving chamber as each additional plate is received.

The above and additional objects are accomplished by such means as are illustrated in the accompanying drawings, described in the following specification, and then more particularly pointed out in the claims which are appended hereto and form a part of this application.

With reference to the drawings wherein I have illustrated the preferred embodiment of my invention as it is reduced to practice, and throughout the several views of which

similar reference numerals designate corresponding parts:

Figure 1 is a side elevation, illustrating the various parts in assembled relation, Fig. 2 is a front elevation of the subject matter of Fig. 1, Fig. 3 is a section on the line 3—3 of Fig. 2, Fig. 4 is a top plan detail view of the name plate receiving magazine, Fig. 5 is a section on the line 5—5 of Fig. 4, Fig. 6 is a detail perspective view of the grabber employed in removing the name plates from the carrier block, Fig. 7 is a detail view of the lower chain drum, illustrating the manner in which the carrier block of the chain removes the name plates from the plate magazine, Fig. 8 is a detail view of one of the name plates, and, Fig. 9 is a sectional view partly on line 10—10 of Fig. 5 particularly illustrating the compartment for receiving the name plates, adjustable block and mechanism therefor.

Proceeding now to the description of the drawings, it may be well for the sake of clearness and in order that a comprehensive disclosure may be had to classify the various elements which, when in assembled relation, constitute the preferred embodiment of this invention. This addressing machine includes, first, the main supporting frame; second, a pair of platen drums; third, a plate conveying chain; fourth, a filling magazine; fifth, a plate receiving magazine; sixth, means associated with this latter magazine for automatically removing the name plates from the chain after they have passed through the platen drums.

Taking up as first in order the description of the supporting frame, this element of the invention may be of any conventional design and in the preferred embodiment it has been found desirable to employ a frame consisting of four upright legs 10, held in the desired rigid spaced relation to each other by upper and lower cross bars 11 and 12, and equipped with additional diagonally directed braces 13 and 14. It has also been found effective to equip the lower terminals of the members 10 with rollers or casters 15 of any desired and suitable type. The upper cross bars 11 of this frame carry a pair of side plates or shields 16 adjacent the lower end of which is journaled the smaller platen roller and at the upper terminal of which is mounted the upper platen roller to be next described. These platen drums are individually designated as en-

tireties in Fig. 1 by the numerals 17 and 18, the numeral 17 designating the upper and larger drum while the numeral 18 designates the smaller and lower drum. These members are of any conventional design and are journaled on suitable shafts which, as previously stated, are journaled in the plates 16 of the main supporting frame. A handle 19 is of course provided for the upper drum 17 for the obvious purpose of actuating the various elements of this addressing machine. In this connection it is to be observed, however, that if so desired, any suitable power source may be operably connected to the upper platen drum by merely applying a cog or gear wheel in the usual manner. In practice, the name plates on which the names have been stamped in the usual manner, are conveyed from their magazine and are passed between the platen drums 17 and 18 through the medium of an endless conveyer consisting essentially in a pair of chains 20. These chains 20 pass over spur wheels keyed to the shaft of the member 18 and also mesh with the spur teeth of a lower chain drum 21, which is journaled on the shaft 22 rotatably supported in suitable bearings 23 carried by the cross bars 12 of the main supporting frame. A block 24 is carried by the chains 20 and is arranged in horizontal position, being adapted to pass completely around the members 18 and 21 during the operation of the machine.

Coming now to the description of the filling magazine which is employed to initially receive the name plates and from which the block 24 receives the individual plates, this feature of the invention as best illustrated in Figs. 5 and 7, includes an angularly supported casing 25 secured to the main supporting frame in any desired manner and arranged with its lower terminal adjacent to the tangential point of the chains 20 with the drum 21. The lower terminal of this member 25 is equipped with a pair of spaced arms or rods 26 which are designed to prevent the displacement of the name plates from the filling magazine by engagement with laterally extending shoulders or lugs 27 which are formed integrally with the name plates, as best illustrated in Fig. 8. Referring particularly to Fig. 8, it will be observed that each name plate consists essentially in a cross-sectional U-shaped metallic body member, on one face of which is stamped or otherwise impressed, the name or address. In practice the name plates are nested within the magazine 25 and are disposed with their lugs 27 arranged in such a manner that the lowermost of the name plates will project partially from the lower terminal of the arms 26. Relative to the manner in which the plates are removed from this filling magazine 25 as the chain

rotates, it will be observed upon reference to Fig. 7, that as the block 24 passes around the lower drum 21 and again starts upwardly toward the platen drums, that the entire range of its upper edge will pass between the arms 26 with the resultant engagement with the portion of the name plate comprehended between the lugs 27. As the block starts to move upwardly due to the rotation of the chains, the forward edge of the next adjacent name plate acts to urge the addressed face of the name plate flat against the block 24. A further description and operation of this machine will be hereinafter further presented.

Proceeding now to the description of the plate receiving magazine, this element of the invention consists essentially in an elongated casing, designated as an entirety in Fig. 5 by the numeral 28. This casing is formed of any suitable and desired sheet metal and is divided into two compartments, respectively designated by the letters A and B, by a horizontal centrally arranged partition wall 29. The chamber A is designed to receive the name plates as illustrated, and is free from all obstructions except for a stop plate 30 which extends transversely of the chamber A and is adjustable longitudinally of the chamber by means of a substantially V-shaped plate 31 which is arranged for sliding movement through a longitudinally extending slot formed in the member 29 and mounted in a plane parallel to the longitudinal axis of the casing 28. As the block 24 approaches the off side of the member 21, through the rotation of the chain, the lugs 27 of the name plate are engaged by the upper terminals 32 of a substantially U-shaped grabbing frame 33, extending rearwardly from the horizontal portion 34 of which is carried a rack bar 35. This rack bar 35 is mounted for sliding movement in a tubular member 36 which is disposed interiorly of and on the bottom wall of the casing 28, as will be readily observed by reference to Fig. 5. The sliding movement of this rack bar 35 is limited through the medium of the stop pin 37 which projects through a slot 38 formed in the tube 36 adjacent its forward terminals and indicated by dotted lines in Fig. 5. Rollers 39 are carried by the free terminals of the arms 40 of the frame 33 and are arranged to engage a cross-sectional triangular shaped cam 41 which is eccentrically mounted on each terminal face of the lower chain drum 21. The rack bar 35 is normally held in extended position with the pin 37 in the forward terminal of the slot 38 by means of an expansion helical spring 42 which is arranged in the tube 36 and at the rear terminal thereof and bearing at one end against the rear wall of the member 28 and at the other against the adjacent terminal 130

of the rack bar 35. In practice the various elements previously described, are arranged in such a manner that as the block 24 brings the lugs 27 of the name plate in engagement with the arms 32 of the grabbing frame, the lower angular face 43 of the member 41 bears against the rollers 39 and urges the rack bar 35 rearwardly against the tension of the spring 42. It will be obvious that such movement of the rack bar 35 will be communicated to the members 32 with the resultant displacement of the name plates from the block 24. It is of course obvious that after the name plates have been removed from the block 24, they will slide down the members 32, lodging in the chamber A of the member 28.

It will now be observed that it is necessary to provide some means for automatically moving the member 30 rearwardly upon the engagement of the rollers 39 with the member 41. In accomplishing this result, there has been provided a pivoted pawl 44 carried by the forward edge of the member 31 and arranged to engage the teeth on the rack bar 35. This pawl is of the gravity type and is in normal engagement with the rack bar 35 so that when this bar moves rearwardly, due to the action of the member 41 on the rollers 39, the member 31, which is mounted for sliding movement on a rod 45, is moved rearwardly through the longitudinal slot of the member 29, with the resultant rearward movement of the member 30. The volume of the receiving portion of the chamber A is thus enlarged to permit the reception of the next name plate, which will be conveyed by the block 24 of the chain, as previously described. Reference to the drawings makes it apparent that as the rack bar 35 moves rearwardly, the member 30 moves through a corresponding distance and a new name plate is deposited in the chamber A. As soon as the rollers 39 have passed the junction of the two inclined faces of the member 41, the member 42 will, of course, act to again force the rack bar out, with the resultant movement of the locking terminal of the pawl 44 into engagement with the next adjacent tooth of the rack bar 35.

A pair of ribbon rollers 49 and 50 are journaled in the upper part of the supporting frame, suitably connected with some revolving part of the machine and adapted to operate a ribbon 51 that is disposed between the platen drums 17 and 18 as will be clearly seen with reference to Fig. 3 in the drawings. It has not been thought necessary to illustrate in detail the ribbon mechanism employed as it does not form a part of the invention.

The actual construction of the various elements of this invention having been thus disclosed, it now remains to describe briefly

the manner in which the names or addresses are printed on the cards or sheets of paper which are manually projected in between the platen drums from a platform or table 46. Reference to Fig. 3 will disclose the exact manner in which the paper is printed. In this figure the numeral 47 designates a sheet of paper which is being drawn between the upper and lower platen drums by reason of their rotation. In this figure it will also be observed that a plate 48 is carried by the upper drum and is designed to compress the paper 47 against the name plate when the block 24 is in its uppermost position.

In reduction to practice I have found that the form of my invention illustrated in the drawings and referred to in the above description as the preferred embodiment, is the most efficient and practical; yet realizing that the conditions concurrent with the adoption of my device will necessarily vary, I desire to emphasize the fact that various minor changes in details of construction, proportion, and arrangement of parts may be resorted to, when required, without sacrificing any of the advantages of my invention, as defined in the appended claims.

Having thus described my invention, I claim:

1. In a machine of the character described, a name plate grabbing frame, said frame comprising a pair of angular spaced vertically disposed arms, a rack bar formed integrally with said frame, a pair of laterally extending spaced arms formed integral with said frame, and rollers mounted upon said last mentioned arms.

2. In a machine of the character described, a plurality of name plates, a name plate receiving magazine, said magazine comprising a casing divided into two compartments, one of said compartments adapted to receive said name plates, means for increasing the receiving capacity of said plate receiving compartment, said means comprising a stop plate slidably mounted within said receiving compartment, and means for operating said stop plate comprising a rack bar slidably mounted within the other of said compartments, means for operatively connecting the rack bar with the stop plate, a spring interposing one terminal of the rack bar and the end of the casing in which it is mounted and means for operating said rack bar.

3. In a machine of the character described, a pair of chains adapted to be rotated, a drum adapted for rotary engagement with said chains, a plurality of name plates, means for individually supporting each of said name plates mounted upon said chains, means for removing said name plates from said supporting means including a pair of angular arms normally disposed for engagement with said name plates, a pair of arms formed integral with said first mentioned

arms, and a cam member mounted upon said drum and adapted for engagement with said last mentioned arms.

4. In an addressing machine, a filling magazine, name plates arranged within said filling magazine, a receiving magazine, means for removing the name plates from the filling magazine, means for automatically removing the name plates from said 10 first named removing means, and means for automatically adjusting the capacity of the receiving magazine comprising a rack bar slidably mounted within said receiving magazine, a stop block slidably mounted 15 within said receiving magazine and operatively connected with the rack bar, a spring engaging one terminal of the rack bar and the receiving magazine, cams operatively connected with the first named removing 20 means and a pair of spaced arms carried by said rack bar and adapted for engagement with the cams.

5. In a machine of the character described, a name plate grabbing frame, said frame

comprising a pair of spaced arms, a rack 25 bar formed integral with said frame, a name plate receiving compartment, said rack bar disposed within the compartment, a pair of spaced arms formed integral with said first named arms and extending at right angles 30 thereto, rollers mounted upon the free terminals of said last named arms, a spring mounted within the compartment between one terminal of the rack bar and one end of the compartment, and means for increasing 35 the receiving capacity of the receiving compartment operatively connected with and actuated by said rack bar and means for operating the rack bar to increase the receiving capacity of said receiving compartment. 40

In testimony whereof I affix my signature in presence of two witnesses.

THOS. F. RUSSELL.
